(57) **CLAIM**

The ornamental design for a candle wick, as shown and described.

DESCRIPTION

FIG. 1 is a perspective view of a first embodiment of a candle wick showing our new design.

FIG. 2 is a front elevation view thereof, the back elevation view being a mirror image thereof, and the side elevation views having the same appearance.

FIG. 3 is a top plan view thereof, the bottom plan view being a mirror image thereof.

FIG. 4 is a perspective view of a second embodiment of a candle wick showing our new design.

FIG. 5 is a front elevation view thereof, the back elevation view being a mirror image thereof.

FIG. 6 is a side elevation view thereof, the opposite side elevation view being a mirror image thereof.

FIG. 7 is a top plan view thereof, the bottom plan view being a mirror image thereof.

FIG. 8 is a perspective view of the candle wick of FIGS. 4-7 shown as a component of a wax candle.

FIG. 9 is a side elevation view of thereof, the opposite side elevation view being a mirror image thereof.

FIG. 10 is a top plan view thereof.

FIG. 11 is a side elevation view thereof, shown with the wax removed, the opposite side elevation view being a mirror image thereof; and,

FIG. 12 is a top plan view thereof, shown with the wax removed.

The broken lines in the drawings are included for purposes of illustrating portions of the environment used with the candle wick that form no part of the claimed design.
